The ornamental design for a reusable litter tray, as shown and described.

DESCRIPTION

FIG. 1 is a top, front and right side perspective view of a reusable litter tray showing our new design.

FIG. 2 is a top, back and right side perspective view thereof.

FIG. 3 is a front elevational view thereof.

FIG. 4 is a back elevational view thereof.

FIG. 5 is a left side elevational view thereof.

FIG. 6 is a right side elevational view thereof.

FIG. 7 is a top view thereof; and,

FIG. 8 is a bottom view thereof.

The broken lines for the trademark "PetSafe" are included for the purpose of illustrating environment and form no part of the claimed design.
